Inventor,
John Brisben Walker,

By *Samuel W. Balch*
Attorney.

UNITED STATES PATENT OFFICE.

JOHN BRISBEN WALKER, OF MOUNT FALCON, COLORADO.

AUTOMATIC ROAD CROWNER.

Application filed December 24, 1920. Serial No. 432,932.

To all whom it may concern:

Be it known that I, JOHN BRISBEN WALKER, a citizen of the United States of America, and a resident of Mount Falcon, in the county of Jefferson and State of Colorado, have invented certain new and useful Improvements in Automatic Road Crowners, of which the following is a specification.

The object of this invention is to provide an apparatus, which by its mathematically calculated construction, will, without the operation of levers or other guidance, when attached to a tractor, or truck, draw the plowed and harrowed land into a symmetrical crown perfect of curvature, leaving no depressions, and shedding the water throughout all ordinary storms, leaving the crown smooth, hard and compact.

A further object is to provide an apparatus which will recrown with mathematical exactness, a highway built under the Brisben Walker specifications, at a merely nominal cost of from fifty cents to one dollar per mile, should there be ruts formed from any cause as for instance heavy trucking during continued wet snows.

A further object is to provide an apparatus which by its simple and inexpensive operation permits the construction of highways of a high economic efficiency.

In the accompanying sheet of drawings which forms a part of this application,

Figure 1 is a plan view of an automatic road-crowner constructed in accordance with this invention.

Figure 2 is an elevation of one of the blades.

Figure 3 is a detail to a larger scale showing the manner of connecting the blades together and to the drawbars.

The automatic road-crowner consists of a front steel blade 10 and a rear steel blade 11 so framed that when dragged behind a tractor or truck moving along the centre of a highway they will produce a perfect road crown, whose curvature corresponds with that of the steel crowner. The blades may be conveniently from fourteen to twenty-two or more feet in length according to the width of road to which it is desired to especially adapt the apparatus. A typical length of eighteen feet is herein selected for illustration of the invention. The blades are one-half inch in thickness by six inches in width and are vertically arched or curved so as to have a six inch rise at the centre

for an eighteen foot length. They are also bent horizontally concave toward the front so that the middle will be about eighteen inches back of the ends. Heavy bolts 12 about five feet in length and one inch in diameter are spaced about four feet apart and parallel and connect the front and rear blades. These pass through holes two inches below the top edges of both blades so as to permit of planks and sand bags being supported thereon. The rear ends of these bolts are bent at right angles and small bolts 13, 13 pass through these ends and the rear blade holding them rigidly at the desired angle. The front ends of the heavy bolts pass loosely through the holes in the front blade and are kept from pulling out the nuts 14, 14 and by reason of the looseness together with a limited flexibility of both bolts and draw bars allow both of the blades to conform more uniformly to irregularities in the general level of the road. A central drawbar 15 and diagonal drawbars 16, 16 of one-half inch by two inch steel are bent at right angles at their rear ends and lie over the top edge of the front blade and are rigidly attached thereto near the middle and at each end by bolts 17, 17, and at their front ends are attached by bolts 18, 18 to a clevis 19. These drawbars are conveniently about 10 or more feet in length according to the width of the blades and the relative lengths of the central and side drawbars are such that the front blade is held by them at the desired concave. The rear blade is held at the same concave by connecting bolts while the apparatus is being dragged on the road. The clevis besides having a central hole is provided with holes about nine inches to either side to either of which the draft chain of a tractor may be attached whenever it is necessary to draw more earth from the other side toward the centre to properly centre the crown of the road.

Planks 20, 20 are laid on the heavy bolts to form a platform which is weighted down with one or more bags of sand as needed. Typical specifications for the construction of a new highway, in which an automatic road-crowner according to this invention is used, are as follows: The centre line of the intended highway is marked by stakes. Commencing adjacent to the centre line the ground is back-furrowed with a twelve or fourteen inch plow for thirteen feet on either side. Then it is re-back fur-

rowed to secure a higher centre and leave wider ditches on either side with the final furrows. The road is next harrowed until 5 clods are thoroughly broken up. With a hand rake all stones and pebbles are carefully dislodged and removed from the road. The ditches are cleaned out to a width of three feet with scrapers and shovels and the material thrown into depressions remaining 10 after the plowing and harrowing so as to bring the road as nearly as possible to a uniform crown with a width of eighteen feet. The road crowner is now used, being drawn by a tractor traveling along the middle 15 of the roadway, and it is drawn back and forth over the stretch of road at this stage of construction until the surface assumes a uniform curvature.

When the crowner is first drawn over the 20 roughly prepared surface there may be portions which have too much crown and other portions where the crown is too little, or there may be a twist in the surface so that one blade may have to drop or rise at one 25 end more than the corresponding end of the other blade. At either of such places there will be an automatic partial adjustment to the actual road crown by reason of the fact that the two blades are not rigidly 30 framed together but are connected by bolts which are more or less yielding and the further fact that the blades are not secured to rigid framework and have some flexibility. At such places the standard crown 35 is reached after the crowner has been drawn over the road a number of times.

The entire road is next rolled, beginning 40 at the edges, with a heavy motor-roller. The road is again gone over with the road-crowner. Next, clean coarse screened sand, free from all stones and pebbles is spread uniformly over the road to a depth of one-half inch. After heavy rains and the use 45 of the road by trucks the automatic road-crowner is again dragged over the road, closing up all ruts and restoring an even crown which will rapidly shed water to both ditches. This should be done as early as 50 possible after the storm. A motor truck or tractor should be able to cover from twenty to thirty miles per day at a cost of about \$10. This large radius of action is important, covering large stretches of road 55 before drying or hardening sets in.

With such treatment, systematically followed, highways can be maintained that in 60 smoothness and hardness of crown closely approach cement crowned highways—this at a cost of one-hundredth part of the expense of building cement highways, and such highways will gain in hardness from year to year and the annual maintenance expense will be nominal. Should the clay at any time show through the sand after heavy use,

a second coating of sand, one-quarter to one-half inch, but not more, may be applied. An essential feature of this system is the binder formed by a small coating of sand with clay, thus creating a species of cement hard surface. The use of larger amounts of sand is injurious rather than beneficial. 65

Since the connecting bolts between the blades in this automatic road-crowner loosely pass through the holes in the front blade and are parallel, the rear blade can 70 be removed from the front blade thus rendering the apparatus more compact for carriage or storage.

I claim,—

1. A yieldingly framed road-crowner 80 comprising vertically arched and horizontally concave front and rear transverse blades each extending continuously from one side of the road to the other, the blades being yieldingly held in edge relation to the road and horizontally concave whereby they 85 automatically adjust their curvature and alignment partially to the road while being drawn thereover.

2. A yieldingly framed road-crowner 90 comprising vertically arched and horizontally concave front and rear transverse blades each extending continuously from one side of the road to the other, draw-bars to the ends of which the front blade is connected, and connecting bolts between the blades the ends of which are connected to the rear blade and loosely connected to the front blade whereby they automatically adjust their curvature and alignment partially 95 to the road while being drawn thereover.

3. A yieldingly framed road-crowner 105 comprising vertically arched and horizontally concave front and rear transverse blades each extending continuously from one side of the road to the other, draw-bars to the ends of which the front blade is connected, and connecting bolts between the blades the ends of which are connected to the rear blade and loosely pass through 110 holes in the front blade by which the blades are held in parallel relation.

4. A yieldingly framed road-crowner 115 comprising vertically arched and horizontally concave front and rear transverse blades each extending continuously from one side of the road to the other, draw-bars to the ends of which the front blade is connected, and connecting bolts between the blades the ends of which are connected to the rear blade and loosely pass through 120 holes in the front blade by which the bolts are held in parallel relation and the blades are held in edge relation to the road and horizontally concave while being drawn 125 thereover.

JOHN BRISBEN WALKER.
